PAUL TATZ, OF BERLIN, GERMANY, ASSIGNOR TO GESELLSCHAFT FUR DRAHTLOSE TELEGRAPHIE M. B. H. HALLESCHES, OF BERLIN, GERMANY, A CORPORATION OF GERMANY.

RAILWAY SIGNALING.

Application filed December 2, 1925, Serial No. 72,649, and in Germany December 6, 1924.

This invention relates to the art of railway signaling and deals particularly with the provision of a railway signaling system which is certain and dependable in its operation.

It is old to provide a travelling train with an electric oscillation generator most suitably an electron tube. For cooperation with this generator there are placed energy absorbing circuits along the tracks such as oscillation circuits tuned to the frequency of the oscillation generator carried by the locomotive and which are so coupled to the device carried by the locomotive that as the same passes over these track devices there is a marked energy absorption and the oscillatory state of the transmitter is thereby altered. A convenient relay or other device is provided to be actuated by this change in the state of the oscillation generator. As a general rule the apparatus has been so designed that the tuned circuit mounted along the track was coupled with a circuit determining the frequency of the tube transmitter. Now in order that sufficient energy absorption may be produced it is necessary to provide for exact tuning between the oscillation circuit along the track and the oscillation circuit of the tube transmitter for the reason that it is possible to attain a transfer of ohmic resistance only if such condition prevails. In the event that there is merely untuning of the circuit the resulting effect is merely an alteration of the frequency of the transmitter or generator tube through the change of the effective inductance of the transmitter circuit. Therefore, if the relay or recording device responds only to energy absorption it is apparent that when detuning takes place between the transmitter and the circuit arranged along the track the apparatus is liable to fail in its operation.

It is an object of this invention to obviate the above disadvantage. This result is obtained by providing the moving train with an oscillation generator and a track device in the usual manner. However, instead of coupling the trackside circuit with the circuit which governs the frequency of the oscillation generator, I provide another separate oscillating circuit to which the track device is designed to be coupled. As a result of this arrangement when the condition of

detuning arises the generator fails completely to oscillate, which condition may be readily indicated by a suitable indicating device. The manner in which I carry out this invention will be better understood from the following description of my system taken in connection with the drawing in which:

The single figure is a diagrammatic view of the train device showing its association with the track device. Referring to the drawing, G represents one of the usual vacuum tube generators which is provided with the circuit S₁ designed to maintain the tube in a state of oscillation. B indicates a suitable source of direct current for the operation of this system; the tube G and the circuit S₁ are arranged in the well-known voltage divider connection. It is well-known that in this form of connection a high frequency resistance must be inserted in the supply lead in order that short circuiting across the battery B may be avoided. It is common practice to use choke coils for this purpose, but in accordance with the present invention I provide a circuit S₂ tuned to the transmission frequency. This circuit S₂ acts as a high frequency resistance and chokes back the radio frequency oscillations generated by the tube G as a result of which the circuit S₁ is enabled to keep the tube G in oscillation. I also provide the relay R which is designed to indicate the fact that the tube has stopped oscillating. The transformer K is associated with the track and is adapted to be coupled to the circuit S₂ as the train passes over the track device.

The operation of the device is as follows:

The circuits S₁ and S₂ are each tuned to the frequency at which it is desired the tube to oscillate. In this condition the relay R will remain in closed position, the plate current passing thru it. As the trackside circuit K is passed over by the train, energy will be absorbed by circuit K and the reaction of circuit K on the inductance coil of circuit S₂ will change the effective resistance of the latter circuit, thereby changing suddenly the plate potential and the plate current. This change of plate potential with respect to the grid upsets the oscillatory condition of the tube and causes it to stop oscillating. The non-oscillatory condition is indicated by its affecting relay R. The position of the relay

thus serves to indicate to the train operator when the train is passing by a trackside device.

Having thus described my invention **I** 5 claim:

In a railway signaling system, the combination of a train device and a track-side device, said train device comprising a vacuum tube oscillator having a plate circuit and

a grid circuit, a tuned circuit in said grid circuit, a battery in said plate circuit, a connection between said battery and an intermediate point of said tuned circuit, a tuned circuit in said plate circuit adapted when reacted upon by said track-side device to render the tube non-oscillatory and means to indicate said non-oscillatory condition.
